UNITED STATES PATENT OFFICE.

EPHRAIM J. DAVIES, OF HIAWATHA, UTAH.

COAL-PICK SHARPENER.

1,107,912.

Specification of Letters Patent. Patented Aug. 18, 1914.

Application filed December 13, 1913. Serial No. 806,555.

To all whom it may concern:

Be it known that I, EPHRAIM J. DAVIES, a citizen of the United States, residing at Hiawatha, in the county of Carbon and State of Utah, have invented new and useful 5 Improvements in Coal-Pick Sharpeners, of which the following is a specification.

This invention is an improved coal pick sharpener or tipper, the object of the invention being to provide an improved machine of this character by means of which a pick after having been heated and forged to a point may have the point tipped while the pick is still hot, so that the pick may be then tempered and put in condition for finishing so that all the work required in the making of the pick may be done in one heat.

The invention consists in the construction, combination and arrangement of devices 20 hereinafter described and claimed.

In the accompanying drawings:—Figure 1 is a perspective view of a pick tipping machine constructed in accordance with my invention, showing the same arranged for use on an anvil. Fig. 2 is a vertical longitudinal sectional view of the same. Fig. 3 is a vertical transverse sectional view of the same. Fig. 4 is a horizontal sectional view of the same on the plane indicated by the 30 line $a-a$ of Fig. 2.

In the construction of my improved pick tipping machine I provide a saddle-shaped base 1 which is adapted to be placed on an anvil such as represented at A, the base of 35 the saddle comprising a plate 2 to bear on the anvil, a depending jaw 3 at one end of the plate for engagement with one side of the anvil and a jaw 4 at the opposite end of the plate for arrangement at the opposite 40 sides of the anvil, said jaw 4 being provided with a clamping screw 5^a for engaging the anvil and clamping the machine firmly thereto. A vertical arm 5 rises from the base plate 2 at the same end thereof with the 45 jaw 3 and this arm has an opening 6 in its center, at a point just above the base. Said arm 5 has angle arms 7 at its lower end, on opposite sides of the opening 6. Said arms 7 form guides and bear on the base plate 2 and are secured thereto by means of bolts 8. A chopping block 9 is arranged between the 50 guide arms 7 with its inner end in the lower portion of the opening 6, the said chopping block being longitudinally adjustable, and 55 being for this purpose provided with a longitudinal slot 10 in which is a set screw 11,

which set screw engages a threaded opening with which the base plate 2 is provided. On the rear side of the arm 5 is a vertically arranged guide casing 12 which is secured to the said arm 5 by bolts 13 and is also secured to the jaw 3 by screws 14. This guide casing is open at its upper and lower ends and serves to hold and guide a vertically movable block 15 on the front side of which is a knife plate 16, said knife plate being provided at its lower end with a beveled cutting edge 17. The knife plate is secured to the block 15 by means of screws 18 and hence may be detached from the block to enable the knife plate to be resharpened or renewed. The knife block has a head 19 at its upper end. The jaw 3 has a substantially L-shaped adjusting and supporting screw 20 secured thereto, the said screw extending up into the lower portion of the guide casing 12 and being provided with an adjustable nut, 21. A cushioning spring 22 is arranged on the said screw and bears on the nut, the upper end of the spring normally extending above the upper end of the screw and normally raising the block 15 so that the knife is held above the chopping block 9.

In the operation of my improved tipping machine, after a coal mining pick has been heated and forged to a point, the point is placed on the chopping block 9 and in the opening 6 and pressed rearwardly against the front side of the knife block and the head of the knife block is then struck by a hammer, thereby causing the knife and the block to be depressed so that the knife tips the point. This operation is performed while the pick is still hot and the pick is then immediately tempered and is ready for 95 finishing so that all the work on the pick is done during one heat.

On the upper end of the arm 5 is a buffer plate 23 which has a flange 24 that bears against the front side of the said arm and is secured by certain of the bolts which also secure the guide casing 12. This buffer plate receives the blow of the hammer after it has been delivered on the head of the knife block.

Heretofore in the manufacture of coal mining picks and other like implements it has been the practice to tip the same on an emery wheel after the pick point has been forged and the pick set aside and cooled, and hence after the picks have been tipped by 110 the use of an emery wheel it has been necessary to reheat them for tempering. By the

use of my improved machine picks may be tipped immediately after their points have been forged and while the pick is still hot, so that the pick can be tempered without re-heating, after tipping in the machine, thus enabling all the work to be done in one heat.

Having thus described my invention, I claim:

- 10 1. A pick tipping machine comprising a base having an arm provided with an opening, a chopping block for insertion in the lower portion of the opening and to bear on the base, a guide casing on the rear side of the said arm, a knife block movable vertically in said guide casing, a tipping knife on said block and movable vertically across the rear side of said opening and a cushioning spring for said knife block.
- 20 2. A pick tipping machine comprising a base having an arm provided with an opening, a chopping block for insertion in the lower portion of the opening and to bear on the base, a guide casing on the rear side of the said arm, a knife block movable vertically in said guide casing, a tipping knife on said block and movable vertically across the rear side of said opening and a cushioning spring for said knife block, and means to adjust said cushioning spring.
- 30 3. A pick tipping machine comprising a base having an arm provided with an opening, a chopping block for insertion in the lower portion of the opening and to bear on

the base, a guide casing on the rear side of the said arm, a knife block movable vertically in said guide casing, a tipping knife on said block and movable vertically across the rear side of said opening and a cushioning spring for said knife block, the said arm of the base being provided at its center with a 40 buffer plate.

4. The herein described pick point tipping machine comprising a saddle base to be fitted on an anvil and having means for securing the saddle to an anvil, an arm rising from 45 said saddle base and having an opening in its lower portion and also provided with guide arms secured on the upper surface of the saddle base and arranged on opposite sides of said opening, a chopping block on 50 said saddle base, between the said arms and with its inner end in the lower portion of said opening, a vertically arranged guide element on the rear side of said arm, a knife block in said guide element and having a 55 knife blade to move across the rear side of the said opening and down to said chopping block, and a cushioning spring for said knife block.

In testimony whereof I affix my signature 60 in presence of two witnesses.

EPHRAIM J. DAVIES.
